(57) **CLAIM**

The ornamental design for a footwear clamp bag accessory, as shown and described.

DESCRIPTION

FIG. 1 is a top, front perspective view of the footwear clamp bag accessory showing our new design in use;

FIG. 2 is a top view of the footwear clamp bag accessory;

FIG. 3 is a bottom view thereof;

FIG. 4 is a side view thereof;

FIG. 5 is an opposite side view thereof;

FIG. 6 is a rear view thereof;

FIG. 7 is a front view thereof; and,

FIG. 8 is a top, front perspective view thereof in use.

The broken lines in the figures depict portions of the footwear clamp bag accessory that form no part of the claimed design. The dot-dash lines in the figures depict environment only and form no part of the claimed design.
